Eugene L. Stott,
INVENTOR
BY Victor J. Evans
ATTORNEY

UNITED STATES PATENT OFFICE

EUGENE L. STOTT, OF CHATTANOOGA, TENNESSEE

NECKTIE

Application filed May 31, 1930. Serial No. 458,169.

This invention relates to certain new and useful improvements in neckwear.

One of the principal objects of the invention consists of a detachable connection for the neck encircling portion of the article of neckwear.

More specifically stated the connection is designed for ultimate disposition within or behind the knot or bow of the article of neckwear to obviate distortion of the wearer's collar and physical discomfort.

With the above and other objects in view, the invention further consists of the following novel features and details of construction, to be hereinafter more fully described, illustrated in the accompanying drawings and pointed out in the appended claims.

In the drawings:

20 Figure 1 is a perspective view of a four-in-hand tie illustrating by dotted lines the position of the detachable connection subsequent to final adjustment of the tie about the neck of the wearer.

25 Figure 2 is an enlarged fragmentary front elevation of the knot formed in the four-in-hand tie disclosing another position of the detachable connection while being passed through the tie knot.

30 Figure 3 is a view similar to Figure 2 showing the detachable connection in elevation without the knot.

Figure 4 is a fragmentary elevation of the component portions of the detachable connection spaced apart.

35 Figure 5 is an enlarged longitudinal sectional view taken through the component portions of the form of detachable connection with the parts assembled.

40 Referring to the drawings in detail wherein like characters of reference denote corresponding parts, the reference character 10 indicates the wide end, 11 the narrower end and 12 the communicating neck band 45 of the conventional form of four-in-hand necktie.

It is my purpose to sever the neck band portion 12 of the tie at a suitable point in the length thereof and to provide an adequate form of separable connection between

the ends thereof which will be entirely obscured from view after the tie has been finally adjusted about the neck and collar of the wearer without causing any degree of discomfort to the wearer or detracting from the general appearance of the collar and tie.

In accomplishing this purpose, I provide sleeve members 13 and 14 inturned, as at 15, at the outermost ends thereof for gripingly engaging the severed portions of the neck band 12 projected for appreciable distances within the bores of each of said sleeves.

As manifest from the illustration of my invention in Figure 5 of the drawings, the sleeve sections are designed for telescopic association, that is, the innermost end of the sleeve 13 accommodates the adjacent end of the companion sleeve within the bore thereof. The portion 16 of the sleeve 14 telescopically associated with the sleeve 13 is provided with transversely disposed parallel slots 17 sufficiently weakening the body of the portion 16 therebetween so as to permit flexing for purposes to be better understood in the following description of the invention.

45 A bead 18 outwardly projecting from the weakened or flexible portion of the body 16 is designed for reception within an annular 80 groove 19 in the sleeve 13. The sleeve 14 is likewise provided with an annular groove 20 forming a shoulder or stop to abut the extremity of the sleeve 13 when the connection is joined in the manner shown in Figure 5 of the drawings. By the particular arrangement of the projection 18 and annular groove 19, it is to be noted that the sections of the connection may be effectively established at any point in the circumference of 85 the sleeves and which may be turned one against the other after the connection has been established therebetween to align the severed ends of the neck band against the inner flap of the collar. After the connection has been established between the ends of the neck band, the narrower end 11 of the tie is then pulled to dispose the knot of the tie in proper position and the connection itself will be drawn through the knot of the

90 tie. After the connection has been established between the ends of the neck band, the narrower end 11 of the tie is then pulled to dispose the knot of the tie in proper position and the connection itself will be drawn through the knot of the 100 tie.

tie and slightly below same in the manner shown in Figure 1. The wider end 10 of the tie will entirely obscure from view the neck band connection.

5 The invention will obviate the usual necessity of untying knots each time the tie is removed and replaced inasmuch as the ends of the neck band portion 12 may be readily disconnected when pulling in opposite directions upon the neck band and the narrower end 11 of the tie to cause the projection 18 to ride out of the annular groove 19. In other words, the original knot formed in the tie may be preserved until the wearer deems it necessary to have the tie cleaned or pressed.

10 The invention is susceptible of various changes in its form, proportions and minor details of construction and the right is herein reserved to make such changes as properly fall within the scope of the appended claims.

15 Having described the invention, what is claimed is:

20 1. As a new article of manufacture, a necktie having the neck band portion thereof severed at an appropriate point in its length, a detachable connection of sectional formation, the sections of the connection carried upon the ends of the neck band being telescopically associated at their adjacent ends, one of these sections having an annular groove adjacent to and within the telescoping end thereof, and a yieldably mounted projection carried upon the other section and disposed within the groove establishing a swivel connection between the sections.

25 2. As a new article of manufacture, a necktie having the neck band portion thereof severed at an appropriate point in its length, a separable connection having the parts thereof carried upon the ends of the neck band for telescopic association at their adjacent ends, one of the parts having an annular groove adjacent to and within the telescoping end thereof, the other part having spaced transversely disposed slots, and a projection yieldably mounted upon the other part between said slots for disposition within the groove to establish a swivel connection between the parts.

30 In testimony whereof I affix my signature.
EUGENE L. STOFF.
